D18176

FIG. 1.

FIG. 2.

UNITED STATES PATENT OFFICE.

FRANCIS A. COFFIN, OF INDIANAPOLIS, INDIANA.

DESIGN FOR A CABINET-DESK.

SPECIFICATION forming part of Design No. 18,176, dated March 13, 1888.

Application filed December 15, 1887. Serial No. 258,037. Term of patent 7 years.

To all whom it may concern:

Be it known that I, FRANCIS A. COFFIN, of Indianapolis, county of Marion, and State of Indiana, have invented a certain new and original Design for Cabinet-Desks; and I do hereby declare that the following is a full, clear, and exact description thereof, reference being had to the accompanying engravings, which illustrate the same.

10 In the engravings, Figure 1 represents a perspective view of my newly-designed desk, all the openings being closed up. Fig. 2 is a similar view of the same, the desk-curtain being rolled back, showing the interior arrangement of the cabinet-top, the slides partly drawn out and the drawers open a little way.

15 The desk itself belongs to that class known as "cabinet" desks; and it consists of a cabinet-top of extra height resting upon a table supported upon pedestals, in each of which is a series of drawers of different widths, one of the pedestals having four and the other three drawers. Above the drawers on each side are extensible slides having beaded edges.

20 The lower drawer in the left-hand side is deeper than those above it, and the lower drawer in the other pedestal is double or more than double the ordinary depth. Between these pedestals is an open central space.

25 The cabinet-top is of more than the usual height, and contains three rows of pigeon-holes, a series of shelves between them, a couple of small drawers connected beneath the pigeon-holes, and an open space between them and the top of the table. The top is closable by a flexible curtain, in the usual manner. The edges of the sides of the top and of the table portion and the slides are molded, as shown. The corners of the pedestals are finished with

30 flat molded pilasters with molded bases and capitals. The fronts of the drawers when closed project beyond the face of the framework and have beveled edges. Plain straight

handles, with beveled edges and rounded ends, are secured to the drawer-fronts, as shown. 45 The small drawers in the cabinet have similar handles, and their fronts are ornamented with plain straight lines, as is also the central piece below the table and between the pedestals. The sides of the pedestals are finished in double 50 panels, the sides of the cabinet-top in single panels.

The leading features of my design consist in the cabinet-top of extra height, having single panels in the ends and inclosing a series of 55 pigeon-holes and small drawers, the pedestals whose drawers have beveled edges and handles of the kind herein described, one of the drawers on one side being of unusual depth, and the slides having their front edges beaded with 60 molding, the whole forming an original and harmonious design, as illustrated in the engravings.

I claim—

The design for cabinet-desks herein shown 65 and described, the sides of the table-top with molded edges, carrying a cabinet above of extra height containing triple rows of pigeon-holes and a pair of small drawers with an open space between and below them, the pedestals supporting the table-top provided with 70 a pair of slides, one of these above each series, the lower drawer in one series being of unusual depth, the drawer-fronts projecting beyond the face of the desk, having beveled 75 edges and plain finish, and provided with plain handles with rounded ends and beveled edges, the corners of the pedestals finished with flat molded pilasters with molded bases and capitals, substantially as shown and described. 80

In witness whereof I have hereunto set my hand this 2d day of November, 1887.

FRANCIS A. COFFIN.

Witnesses:

C. P. JACOBS,
E. B. GRIFFITH.
